AIRCRAFT ANTENNA MAST

William C. Rogers, Miami Springs, Fla.
(P.O. Box 48-205, Miami, Fla. 33148)

Filed Dec. 16, 1968, Ser. No. 14,988

Term of patent 14 years

Int. Cl. D14—03

U.S. Cl. D26—14

FIG. 1

FIG. 2

FIG. 3

FIG.4

FIG.5

FIGURE 1 is side elevation of an aircraft antenna mast showing my new design;

FIGURE 2 is a top plan view thereof;

FIGURE 3 is a bottom plan view thereof;

FIGURE 4 is a front elevation thereof; and

FIGURE 5 is a back elevation thereof.

The broken lines are shown for illustrative purposes only.

I claim:

The ornamental design for an aircraft antenna mast, substantially as shown and described.
